F. L. LOOKE,
RADIATOR PIPE PLIERS,
FILED Oct. 18, 1921.

Inventor

F. L. Looke.

By

Lucy Looke, Attorney

UNITED STATES PATENT OFFICE.

FRANK L. LOOKE, OF BRUSETT, MONTANA.

RADIATOR-PIPE PLIERS.

Application filed October 18, 1921. Serial No. 508,438.

To all whom it may concern:

Be it known that I, FRANK L. LOOKE, citizen of the United States, residing at Brusett, in the county of Garfield and State 5 of Montana, have invented certain new and useful Improvements in Radiator-Pipe Pliers, of which the following is a specification.

This invention relates to improvements in 10 pliers and has as one of its principal objects to provide a device of this character particularly adapted for use in repairing the radiator tubes of Ford motor vehicles.

The invention has as a further object to 15 provide a device of this character whereby the pliers may be readily inserted between the fins of the radiator without likelihood of injury to or displacement of said fins.

And the invention has as a still further 20 object to provide graduations upon the pliers whereby the pliers may be readily positioned from either the front or back of the radiator to engage a particular tube.

Other and incidental objects will appear 25 hereinafter.

In the drawing:

Figure 1 is a plan view illustrating the manner in which my improved pliers are employed, a portion of a Ford radiator being 30 conventionally shown in horizontal section, and

Figure 2 is a perspective view of the pliers.

As is well known, owners of Ford motor 35 vehicles often experience considerable trouble and expense owing to the extreme difficulty in repairing leaky radiator tubes, caused through bursting of said tubes by freezing of the water therein or from other reasons. Accordingly, I seek to overcome this difficulty by providing a tool which may be conveniently and easily manipulated for operating upon any one of the tubes damaged.

In carrying the invention into effect, I employ 40 companion crossed levers formed to provide oppositely curved operating handles 10 pivoted at their point of intersection by means of any suitable pivot element 11 and formed on said levers at their forward ends

50 are elongated jaw shanks 12 which lie in a plane common to both thereof. These jaw shanks are flat and relatively thin, being provided with flat smooth faces and being tapered in width and thickness to permit of ready insertion of the shanks between the fins of a radiator, it being observed in this

connection that the pivot element 11 is disposed at substantially a right angle to the flat faces of the jaws. The outer terminals of the shanks are slightly flared and are 60 curved inwardly toward each other to provide confronting gripping jaws 13 adapted to abut in mating relation. Formed in each of the jaws is a semi-circular recess 14, these recesses, when the jaws are brought together, serving to define a circular opening, which opening is of an internal diameter substantially equal to the external diameter of a Ford radiator tube to thus snugly receive such a tube. Arranged upon the upper 65 sides of the jaw shanks are corresponding longitudinally spaced graduation marks 15, 16 and 17, respectively.

In Figure 1 of the drawing, I have illustrated my improved pliers in connection 75 with a Ford radiator, conventionally shown at 18. In this figure, I have shown the jaws 13 of the pliers engaged about one of the tubes in the front row of tubes of the radiator, said jaws being disposed at opposite 80 sides of the tube and meeting in abutting relation. Since, as previously intimated, the circular opening defined by the recesses 14 in the jaws is of an internal 85 diameter substantially equal to the external diameter of the tube, a tube which, for instance, has burst due to freezing of the water therein, will thus, when the jaws are brought together as shown, be pressed back into its original shape. Further, in this connection, 90 it is to be particularly noted that pressure may be exerted upon the jaws of the pliers without fear of crushing the wall of the tube inwardly beyond the proper point. For properly positioning the pliers to engage 95 the different tubes of the radiator from either the front or rear thereof, I provide the graduations upon the jaw shanks. For instance, as will be observed by reference to Figure 1, by alining the graduation marks 100 15 with the front edge of the adjacent one of the fins of the radiator, the jaws 13 will be disposed to reach the tubes of the front row of tubes as just described. Should it be desired to operate upon the next row of 105 tubes, the graduation marks 16 are alined with the front edge of the fin, the jaw shanks being spaced apart so as to straddle any one of the tubes in the front row, or when the device is used to operate upon the third row 110 of tubes, to straddle alined tubes in the first and second rows. As will be appreciated,

by forming the jaw shanks and jaws flat and thin the pliers may be readily inserted between the fins of the radiator while for greater convenience I have found it preferable, instead of inserting the pliers entirely through a radiator from one side to the other, to operate upon three rows of tubes from one side and two rows from the other side, or vice versa.

10 Having thus described the invention, what is claimed as new is:

A tool of the character described including pivotally connected levers provided with jaw shanks terminating in coacting jaws

extending inwardly toward each other beyond the inner longitudinal edges of the shanks and provided with mating recesses for the reception of an automobile radiator tube, the jaw shanks being spaced apart when the jaws are closed whereby said jaw shanks may straddle one or more tubes of the radiator having said jaws engaging another of said tubes, and means upon one of the jaw shanks for locating the jaws to engage a predetermined tube of the radiator.

In testimony whereof I affix my signature.

FRANK L. LOCKE. [L. S.]
